UNITED STATES PATENT OFFICE.

WALTER BURNHAM, OF CHICAGO, ILLINOIS.

STEAM-BOILER-FEEDING DEVICE.

SPECIFICATION forming part of Letters Patent No. 394,828, dated December 18, 1888.

Application filed February 21, 1888. Serial No. 264,812. (No model.)

To all whom it may concern:

Be it known that I, WALTER BURNHAM, of Chicago, in the county of Cook and State of Illinois, have invented certain new and useful 5 Improvements in Steam-Boiler-Feeding Devices; and I do hereby declare that the following is a full, clear, and exact description thereof, reference being had to the accompanying drawing, and to the letters of reference 10 marked thereon, which forms a part of this specification.

This invention relates to devices for delivering liquids from a space or chamber subject to one pressure into a chamber subject to a 15 higher pressure—as, for example, the delivery of water from an open tank or from a hydrant into a steam-generator.

The object of the invention is to adapt the 20 method set forth in an application for Patent, Serial No. 263,225, filed by William Irving, February 7, 1888, to situations where it is impracticable to employ a single return or lifting pipe of such height as to give a water 25 column sufficient to balance the different pressures from the less to the greater of which the liquid is to be transferred.

In the accompanying drawing illustrating 30 my invention, a steam-generator, and a series of chambers or vessels subject to graduated pressures are shown in vertical section and the pipe-connections thereof are shown in side elevation.

A is a generator, subject, say, to thirty 35 pounds pressure; and B, C, and D are tanks, subject to, say, twenty pounds, ten pounds, and one pound, respectively, above the atmosphere.

E represents a pipe leading into the tank D of lowest pressure from the elevated open 40 tank E', or any other source of supply adapted to deliver water into said tank D.

F is a steam-pipe connecting the generator with each of the several tanks, B C D, in any suitable way, and F' F² F³ are reducing- 45 valves set to give in the several tanks the desired degree of pressure, these connections being shown as one form of practicable means for establishing in the tanks the graduated pressures described.

50 G G' G G' G' are similar "return" or transfer pipes, each for transferring water from one chamber to the chamber of next

higher pressure by means of a steam-flow, as set forth in said Irving's application for patent, but here shown as being provided with certain improvements at their receiving ends, as set forth in another application for patent filed by me of even date herewith—that is to say, each transfer-pipe comprises an ascending portion, G, having a drainage-connection 55 with a tank, (as B,) and a descending portion, G', which enters the generator or a tank of higher pressure, the said descending portion containing a water column of height due to the difference in pressure to which the opposite ends of said water column are subject. Above the water column in the descending leg G' is a space within the transfer-pipe, of less pressure than that of the tank from which it leads and in steam communication with said 60 tank. Such less pressure may be the result either of radiation and condensation alone or of condensation assisted by escape through a valved discharge, g, or by escape alone, as in the case of a non-condensable fluid like air. 65 By reason of such relatively-low pressure in the lifting-pipe above the water column, steam is caused to flow up the rising member G with greater or less rapidity, and in its flow it carries along with it small bodies of water admitted to the lower end of said member. The 70 water so lifted is deposited in the leg G' and ultimately enters the water-body in the tank or generator entered by said leg.

The difference in pressure between the low-pressure space in the lifting-pipe and that in the chamber from which it proceeds must manifestly be sufficient to cause a steam-flow adequate to the raising of the amount of water to be transferred. It is further manifest 75 that the "drop-leg" or descending member G' of the lifting-pipe must be long enough to contain the water column due to the difference in pressure between the said low-pressure chamber and the generator or tank of higher pressure. It follows that when water is to be transferred to a generator, (for example,) taken from a chamber subject to a greatly less pressure than that of the generator, if a single transfer-pipe be used the latter must rise to 80 a height above the water-level in the generator proportioned to this difference in pressure. Space for such an ascent may not be available; or, if space be available, other ob-

jections to its use may be present. Wherefore an intermediate tank or a series of intermediate tanks with graduated, though not necessarily uniform, increase of pressures is introduced, as shown, the difference of pressure between any two adjacent or connected tanks of the series being so small that a comparatively low transfer-pipe, $G G'$, may be used.

10 Thus in the drawing a pipe, $G G'$, connects the tank D with the tank C, which pipe has a vertical length of drop-leg G' , adapted to contain a water column (above water-level in C) only, or, for safety, little more than equal to the balancing of pressures differing by nine pounds, this being the difference between the pressures assumed to be established in said tanks, respectively, by the reducing-valve F^3 . So between tanks C and B there is a difference in pressure of ten pounds, and between the tanks B and A there is also a difference of ten pounds, and the return or lifting pipes connecting C and B and B and A are adjusted in height to proximate this difference in pressure. While each pipe $G G'$ is therefore adapted to a water column not much higher than is due to a difference of ten pounds, they are together adapted to contain an aggregate of twenty-nine pounds of water head with a corresponding lifting capacity, so that by their aggregate energies water is carried to the generator A against twenty-nine pounds greater pressure than that of the tank D from which it is taken.

35 Manifestly any number of intermediate tanks may be employed in the series, and their differences in pressure may be made so small that water may be automatically fed by the apparatus from any source of supply under some degree of pressure to a generator, A, no matter how high the pressure to which the latter may be subjected.

The pipe E, which supplies water to the tank D, is here shown in full lines as leading 45 from a tank, E', open to the atmosphere, and itself fed from a faucet, e, discharging from a pipe, E^2 , or from an exhaust-pipe, E^3 , leading from an engine. The head on the pipe E must in this case be equal to the delivery of 50 water against the one-pound pressure above atmosphere in the tank D. The pipe E is shown in dotted lines as connected directly with the pipe E^2 , which may be supposed to be under pressure, as when connected with a 55 city water-supply system. The pipe E may also be understood to be part of the return-pipe of said Irving system, and D the low-pressure chamber of that return. The tanks C B, &c., and the pipes $G G'$ become in that 60 case the continuation of the Irving return-pipe. The power of the Irving return system may thus be very greatly augmented, while occupying but little vertical space for the water columns.

65 As explained in my before-mentioned application for patent, the two entrance-pipes, g^2 and g^3 , respectively for water and steam,

and provided with valves, as shown, are for the better control of the movements of water and steam through the lifting-pipe, of which 70 they form part.

The apparatus will manifestly operate in connection with the return of a steam-heating apparatus, or when steam instead of water, or steam and water, are supplied to the tank D. 75 It will also operate if the valve e' be closed and the reducing-valves $F F'$, &c., are omitted, or are fully opened, so as to admit steam at, or practically at, boiler-pressure to each of the tanks. If the valves $F F'$, &c., be adjusted to give graduated pressures in the series of tanks, and steam, or steam and water, or water alone, be supplied to the tank D at first at a high or even full boiler-pressure, and the pressure of such supply be gradually or 80 suddenly reduced, the apparatus will work, and will adjust itself to such change of pressure in the water or steam supplied by automatic variation in the water-legs. In short, the apparatus will, by means of such variable 85 water columns, adjust itself automatically to any order of changes in pressure on the tank D.

It is to be understood that under the term "steam," as herein employed, is to be included any other fluid with which the apparatus will operate.

I claim as my invention—

1. The combination, with a generator or chamber under pressure and a liquid-supply pipe under pressure less than that of the 100 generator, of a tank connected with and receiving from the supply-pipe and subject to steam-pressure in degree intermediate to those of the generator and supply-pipe, and a transfer-pipe taking steam and liquid from 105 the tank and connected at its opposite end with the generator, said transfer-pipe having a descending portion, which contains a liquid column due to the unequal pressures above and below said column.

2. The combination, with a liquid-supply pipe, as E, subject at its delivery end to pressure, and a steam generator or chamber subject to a pressure greater than that of the supply-pipe, of a tank, D, having a receiving- 115 connection with the supply-pipe, a steam-pipe leading from the steam generator or chamber to the tank D, and provided with a reducing-valve, and a transfer-pipe connecting the tank and steam-chamber, and provided 120 with a descending portion, G' , containing a water column due to the difference in pressures above and below said column.

3. The combination, with a steam-generator, of a series of tanks or chambers, steam-connections provided with reducing-valves, whereby graduated pressures lower than that of the generator may be established in the series of tanks, a series of rising and descending transfer-pipes, each taking water and 130 steam from one tank and discharging into the water-space of the tank or chamber of next higher pressure, and means for delivering water into the tank of lowest pressure.

4. The combination, with a chamber subject to steam-pressure and a chamber subject to lower steam-pressure, of a chamber subject to an intermediate steam-pressure, a transfer-
5 pipe taking steam and liquid from the chamber of lowest pressure and discharging into the chamber of intermediate pressure, said pipe having a descending portion which con-
10 tains a liquid column due to the unequal pressure above and below it, and a similar

transfer-pipe connecting the chamber of intermediate pressure with the chamber of highest pressure.

In testimony that I claim the foregoing as my invention I affix my signature in presence 15 of two witnesses.

WALTER BURNHAM.
